[57] CLAIM

The ornamental design for a combined handle-operated flow control valve and pressure gauge, as shown and described.

DESCRIPTION

FIG. 1 is a left side elevational view of a combined handle-operated flow control valve and pressure gauge showing my new design;

FIG. 2 is a top plan view thereof;

FIG. 3 is a right side elevational view thereof;

FIG. 4 is a bottom plan view thereof;

FIG. 5 is a front end elevational view thereof; and

FIG. 6 is a rear end elevational view thereof.

The shaft portion is shown broken-away in the views to indicate indeterminate length.

FIG. 1

FIG. 2

FIG. 3

FIG. 4

FIG. 5

FIG. 6
